UNITED STATES PATENT OFFICE.

DAVID W. HAWKSWORTH, OF DETROIT, MICHIGAN, AND FREDERICK M. WHYTE, OF TARRYTOWN, NEW YORK, ASSIGNEES TO HUTCHINS CAR ROOFING COMPANY, OF DETROIT, MICHIGAN, A CORPORATION OF MICHIGAN.

CAR-ROOF.

1,255,309.

Specification of Letters Patent. Patented Feb. 5, 1918.

Application filed November 15, 1913. Serial No. 801,288.

To all whom it may concern:

Be it known that we, DAVID W. HAWKSWORTH and FREDERICK M. WHYTE, citizens of the United States of America, residing at 5 Detroit, Wayne county, Michigan, and Tarrytown, Westchester county, New York, respectively, have invented certain new and useful Improvements in Car-Roofs, of which the following is a specification, reference being had therein to the accompanying drawings.

The invention relates to car roofs of that type in which load-sustaining metallic roofing plates are flexibly connected to each 15 other with a weather-proof joint permitting of relative adjustment under the weaving action of the car frame. It is the object of the present invention—first, to obtain greater flexibility or freedom of relative adjustment of the plates; second, to more securely fasten or hold down the plates to the roof frame; third, to produce a more thoroughly weather-proof construction; and fourth, to improve the construction of various specific features as hereinafter set forth.

In the drawings:

Figure 1 is a cross section through a portion of the car roof on line $x-x'$ of Fig. 5 showing our improved construction;

Fig. 2 is a plan view thereof;

Fig. 3 is a side elevation;

Fig. 4 is an enlarged section through a portion of the roof adjacent to the eaves;

Fig. 5 is a cross section on line $x-x'$ of Fig. 4;

Fig. 6 is a section similar to Fig. 4, showing a modified construction; and

Fig. 7 is a perspective view of a portion of one of the roofing sheets and a portion 40 of the weather cap for engagement therewith.

With the type of roof to which the present invention belongs a series of load-sustaining metallic roofing plates are so supported upon the car frame as to have a limited independent movement in the plane of the roof. It is essential, however, to securely fasten these plates down upon the roof frame, and also to thoroughly weather proof the joints between plates and at the eaves of the car, this having been accomplished heretofore in various ways, all of which are not wholly satisfactory. One of the difficulties encountered is to provide

a holding down means for the plates at the 55 eaves, which may be easily applied and which permits of readily detaching the plates when necessary for repairs, and which is scientifically correct.

The present invention accomplishes these 60 objects by dispensing with the usual laterally-extending securing bolts and substituting therefor vertically extending securing devices. Inasmuch, however, as it is essential 65 to provide freedom of movement for the roofing plates, these vertical securing bolts are not engaged directly therewith, but are attached to the weather-proofing means and through the medium of the latter draw down upon the roofing plates to hold the same 70 upon the roof frame.

In addition to the advantageous feature just described our improved construction of roof has a further advantage of providing a thoroughly weather proof joint at the 75 eaves, and yet one which does not interfere with the freedom of movement of the roofing plates. A still further advantage is the dispensing with the usual fascia which protects the upper edge of the sheathing of the 80 car side. Still further, various details of construction have been improved as herein-after set forth.

A is the side plate of the car body. B are the carlines connecting said side plates 85 and preferably attached thereto by brackets C. As preferably constructed the carlines B are of inverted U cross section, with outwardly-extending base flanges, and are secured to the brackets C by riveting or bolting. The bracket C is preferably secured to the side plate A by vertical and transverse bolts D and E, as shown in Fig. 4.

F are roofing plates, preferably formed of relatively heavy gage metal and supported upon purlins F' which are secured to the carlines B. Each of these roof plates is formed with upstanding marginal side and ridge flanges M and downturned eave flange J, which latter is inwardly - returnbent to 100 form an open groove. G are metallic strips which are secured to the side plate A and are preferably of a Z-shape cross section, the intermediate web of which extends over the upper edge of the siding of the car body. 105 G' is the downturned flanges on the strip G which engages the groove in the returnbent portion I of the plates F, as shown in Fig.

4. These strips G perform several functions; one function is that of a stop to limit the movement of the plates F in the plane of the roof, the amount of movement thus permitted being equal to the width of the groove formed by the returnbent flange I. Another function of the strips G is that of a flashing or weather proofing means, which prevents the flowing of rain in between the depending flange J of the roof plates and the side of the car. Still another function of the strips G is that of a fascia for protecting the car siding.

The plates F extend between the carlines B, with the provision of sufficient clearance for the lateral movement of said plates. At the carlines the adjacent roofing plates are weather-proofed by caps N which embrace the upstanding flanges M of said plates and are provided with foot flanges M' for bearing on said plates. The caps N, in addition to weather-proofing the joint between the sheets, form the holding down means for the roof on the car frame. To this end they are secured to the carlines, preferably by shoulder bolts P. These are preferably riveted or otherwise secured to the caps N and extend downward therefrom through apertures in the carline B, being clamped to the latter by nuts P' located in the channel or groove of the carline. The shoulder portion P² of these bolts operates as a spacer, so that the cap may be securely clamped in position without drawing downward upon the roofing plates beyond a predetermined point. This will hold the plates down without interfering with their freedom of movement.

The caps N at the eaves are formed so that the channel section gradually merges into a downturned flange O lying adjacent to the downturned flange J of the roofing sheets, and an inturned flange O' passes beneath the returnbent portions I of the roofing plates. Both the flanges O and O' overlap the edges of the roofing plates so as to form a weather joint. At the ridge, the upstanding flanges M of the plates F are overlapped by U-shaped ridge caps Q, and the ends of these caps, together with the upper ends of the carline caps N, are secured to the ridge purlin by junction caps R.

With the construction described, in assembling the roof, the carlines are first placed in position and are secured by means of the brackets C. The strips G are also laid along the edge of the side plate A and are secured thereto by nailing or otherwise fastening the upwardly-extending flange G².

This flange does not extend beyond the top of the side plate A and therefore will not cut into the roofing plates supported on said side plate. A depending flange C' on the bracket C overlaps the flange G² and

this engagement has the double advantage, first, of forming an extended metallic bearing for the flange C'; and second, the holding down of the flange G² so that it cannot rise to cut or abrade the roofing sheets.

After the carlines and strips G are in position, the roofing plates may be laid, by first engaging the returnbent flange with the depending flange G' of the strip G and then turning the plate F downward until it lies upon the purlins. The caps N are then placed in position and are secured from the inside of the car by engagement of the nuts P' with the bolts P. The ridge caps Q and junction caps R may then be secured in position, after which the roof is securely held against vertical displacement.

In operation great flexibility is secured by reason of the fact that each of the plates F is entirely free from lateral connection with the roof frame. This freedom of movement is limited by the carlines at the sides of the plates and by the depending flange J and returnbent flange I. Sufficient clearance is, however, provided to take care of the maximum distortion to which the car frame is subjected and consequently there is nothing to twist or distort the roofing plates when the car is in service.

The caps N are of a cross section which will provide clearance for the inverted U-shaped section of the carline as far as this section is maintained. At the eaves, however, the carline proper terminates at the inside of the side plate of the car, while the bracket C is tapered from this point to the outer face of the side plate. This permits of forming the cap with a portion O² which gradually changes from the inverted U-section above the carline to the flat vertical flange O which overlaps the flanges J of the roofing plates. This results in a tapering portion O³ from the top of the inverted U to the point of merger with the side flanges N', and a rounded portion O⁴ at the corner, and to increase the strength of this corner a depressed portion O⁵ is formed centrally therein to produce a bracing effect.

For securing the brackets C to the side plates the bolts E are preferably provided with squared heads. To prevent accidental turning of these bolts and the loosening of the same from the clamping nuts on the inside of the car, these square heads are arranged to bear against the underside of the strip G and thus when the strip is in position the bolt is locked from turning.

What we claim as our invention is:

1. In a car roof, the combination with carlines of load-sustaining metallic roofing plates extending from ridge to eave and spanning the spaces between said carlines

and having a limited freedom of movement in the plane of the roof in all directions, and weather-proofing means between said plates constituting the sole active holding down means therefor.

2. In a car roof, the combination with carlines of load-sustaining metallic roofing plates extending from ridge to eave and spanning the spaces between said carlines and provided with clearance for free movement in all directions, in their respective planes, means at the eaves for limiting the freedom of movement of said plates, and weather-proofing means between said plates constituting the holding down means therefor.

3. In a car roof, the combination with carlines of load-sustaining metallic roofing plates extending from ridge to eave and spanning the spaces between said carlines, said plates being provided with upstanding flanges at their side edges and a downturned flange at the eave, with clearance for limited movement in their respective planes in all directions, weather-proofing caps embracing the upstanding flanges of adjacent sheets, and means for securing said caps to said carlines, whereby the caps constitute the sole active holding down means for said plates.

4. In a car roof, the combination with carlines of carline caps, a vertical tie connection between said carline cap and carline, and roofing plates extending from ridge to eave and spanning the spaces between said carlines with a limited freedom of movement in their respective planes in all directions, said plates being held down solely by caps and being weather-proofed thereby.

5. In a car roof, the combination with carlines of load-sustaining metallic roofing plates extending from ridge to eave and spanning the spaces between said carlines and provided with upstanding top and side flanges and a downturned eave flange, weather-proofing caps embracing said carlines and upstanding side flanges of adjacent plates, and means engaging said eave flange for weather-proofing the roof at the eaves.

6. In a car roof, the combination with a load-supporting roofing plate having a limited freedom of movement in all directions in the plane of the roof, of a return-bent eave flange on said plate, a flashing forming a weather-proofing joint with the return-bent portion of the plate, and means independent of the flashing for limiting the movement of the plate.

7. In a car roof, the combination with a load-sustaining metallic roofing plate having a limited freedom of adjustment in all directions in the plane of the roof, of an eave flange having an open return-bend, a flange secured to the car having a portion extending into the open return-bent portion

of the eave flange, and means independent of said flanges for limiting the movement of said plate.

8. In a car roof, the combination with carlines, of load-sustaining metallic plates spanning the spaces between said carlines and having a limited freedom of movement in the plane of the roof, said plates having a weather-proofing joint at the eaves, permitting of their movement in the plane of the roof, said plates being provided with upstanding flanges at their side edges, carline caps embracing said flanges and vertically extending means for securing said caps to said carlines and limiting the movement of said plates independent of the weather-proofing joint at the eaves.

9. In a car roof, the combination with the side plate of the car and siding secured thereto, of a metallic bar secured to said side plate and having a portion overlapping the upper edge of said siding and a depending flange spaced from said siding, and a freely movable roofing plate provided with a depending eave flange having an inward open return-bend, said bend being engageable with the depending flange of said strip and providing clearance for movement of said plate.

10. In a car roof, the combination with carlines, of a series of load-sustaining roofing plates spanning the spaces between said carlines and provided with upstanding side flanges, a depending eave flange, an inward, open return-bend on said eave flange, a metallic strip secured to the side plate of the car having an outwardly-extending portion overlapping the upper edge of the car siding and a depending flange spaced from said siding and loosely engaging the open return-bend of said plates, and carline caps embracing said carlines and upstanding side flange of said roofing plates, the ends of said caps merging into a depending eave flange overlapping the adjacent eave flanges of the plates and terminating in an inwardly-bent flange.

11. In a car roof, a weather-proofing carline cap having a main portion of inverted U-shaped section with outwardly-extending base flanges, the end portion of said cap being of a changing section merging into a common vertical plane to form a depending eave flange with an inwardly-bent flange at its lower end.

12. In a car roof a weather-proofing carline cap having a main portion of inverted U-section with outwardly-extending base flanges, the end portion of said cap being of a changing cross section merging into a common plane forming a rounded corner and depending eave flange, the central portion of the metal at the rounded corner being depressed to form an inner brace therefor.

13. In a car roof, the combination with the side plates of the car, of carlines, brackets for connecting said carlines to said side plates, having a portion lying adjacent to the inner face of the side plate, a portion overlapping the top of said side plate and a depending flange engaging the outer face of said side plate, a series of roofing plates having depending eave flanges with inward, open return-bends, and a metallic strip of Z-bar section having a depending flange engaging said return-bends and an upwardly-extending flange between said depending flange on said bracket and said side plate forming an extended bearing for the former and being held from upward movement thereby. 50
14. In a car roof, the combination of the side plate of the car, carlines, a series of roofing plates intermediate said carlines and provided with depending eave flanges having inward, open return-bends, a strip of Z-bar section having a downwardly-extending flange engaging said bends and an upwardly-extending flange secured to said side plate, and a bracket for securing said carline to said side plate having a downwardly-extending flange overlapping said upwardly-extending flange of said Z-bar for the purpose described. 55
15. In a car roof, the combination with carlines of inverted U-section, load-sustaining roofing plates upon opposite sides of said carlines and movably supported on the roof frame, a cap embracing said carline and the marginal portion of said roofing plates, a securing bolt permanently attached to said cap, passing through a registering aperture in said carline, and locking means for said bolt engageable therewith from inside the car in the channel of the carline, whereby said cap forms a holding-down means for said plates. 60
16. In a car roof, the combination with carlines, of a series of load-sustaining, relatively movable roofing plates, weather-proofing caps embracing said carlines and the marginal portions of said roofing plates, holding down means for said roofing plates including a bolt permanently secured to said cap and passing through a registering aperture in the carline, and locking means for said bolt engageable therewith in the channel of said carline from the inside of the car. 65
17. In a car roof, the combination with the car side-plate, of carlines, brackets for securing said carlines to said side plate, roofing sheets between said carlines having downwardly-extending return-bent eave flanges, a bolt extending laterally through said side plate for securing said bracket thereto and provided with a square head at its outer end, and a strip secured to the side-plate of the car having an outwardly-extending portion overlapping the upper edge 70 of the car side and bearing against the head of said bolt, said strip being also provided with a downturned flange spaced from said siding and engaging the open return-bend of said plate. 75
18. In a car roof, the combination with carlines, of relatively movable roofing plates, weather-proofing caps embracing said carlines and the marginal portions of said roofing plates, and shoulder bolts permanently attached to said caps and connecting said weather-proofing caps and carlines to each other, operating as a spacer between the two members. 80
19. In a car roof, the combination of the side plate of the car, carlines, a series of roofing plates intermediate said carlines and provided with depending eave flanges having return-bends, a strip engaging said return-bends and secured to said side plate, and a bracket for securing said carline to said side plate having a downwardly-extending flange overlapping a portion of said strip. 85
